CLAIM

The ornamental design for an accessory for a welding machine as shown and described.

DESCRIPTION

FIG. 1 is a front, top and right side perspective view of an accessory for a welding machine, showing our new design; FIG. 2 is a left side view thereof;

FIG. 3 is a bottom view thereof;

FIG. 4 is a right side view thereof;

FIG. 5 is a top view thereof;

FIG. 6 is a rear view thereof; and,

FIG. 7 is a front view thereof.

The features shown in broken lines depict portions of the accessory for a welding machine that form no part of the claimed design.

1 Claim, 7 Drawing Sheets
